(57) CLAIM

The ornamental design for decorative features for a shoe, substantially as shown and described.

DESCRIPTION

FIG. 1 is a perspective view of decorative features for a shoe showing my new design.

FIG. 2 is a side view thereof.

FIG. 3 is a side view thereof; and,

FIG. 4 is a rear view thereof.

The broken lines of FIGS. 1, 2, 3, and 4 depicting a shoe are ornamental and form no part of the ornamental design claimed.

1 Claim, 2 Drawing Sheets
